UNITED STATES PATENT OFFICE

JOHN W. GARDNER, OF QUINCY, ILLINOIS, ASSIGNOR, BY MESNE ASSIGNMENTS, TO
GARDNER-DENVER COMPANY, A CORPORATION OF DELAWARE

PUMP

Application filed March 2, 1926. Serial No. 91,740.

My invention relates to pumps. It has for its object to provide an improved pump, and more particularly an improved pump of a type adapted to oil field work, as, for example, the pumping of mud fluid or high pressure oil line pumping. A further object of my invention is to provide a pump of an improved construction wherein it is made possible to increase the efficiency by minimizing the friction, not only in the suction and discharge passages leading to the valves, but also in the passages leading from the discharge valves. Another object of my improvement is to provide a simplified construction which, while exceedingly rugged and enabling the above advantages to be obtained, is so arranged as to be economically manufactured and to reduce the cost of upkeep, replacement of broken parts, including the cylinders, being made possible with a minimum of difficulty and expense. A still further object of my invention is to provide an improved construction for a so-called water or pumping end of a duplex pump having the above characteristics and enabling a highly efficient, yet simple and rugged double acting duplex pump construction to be produced. These and other objects and advantages of my construction will, however, hereinafter more fully appear.

In the accompanying drawings I have shown, for purposes of illustration, one form which my invention may assume in practice.

In these drawings,—

Figure 1 is a perspective view of my improved pump taken as a whole, including the power or steam connections therefor;

Fig. 2 is a plan view of the so-called water end of the pump;

Fig. 3 is a side elevation of this water end;

Fig. 4 is a vertical sectional view on line 4—4 of Fig. 5;

Fig. 5 is an end elevation of the water end, partially in section, the section being taken on line 5—5 of Fig. 2;

Fig. 6 is a diagrammatic view showing the flow to the suction valves; and

Fig. 7 is a diagrammatic view showing the flow from the discharge valves.

In this illustrative construction, I have

shown my invention embodied in a duplex steam driven pump of a generally familiar type including a usual steam end 1 having suitable valve mechanism operated through valve gear 2, which is in turn connected to a part on each of the usual rods 3 of the usual pistons operating in a well known manner in both the steam and water cylinders, this so-called steam end also including, herein, a usual frame 4 supported on a foot 5 and being connected at one end to an improved water end 6, hereinafter more specifically described. Inasmuch as the steam end per se does not enter into this invention, and this steam end may be of any suitable construction or, in fact, may be replaced by any suitable or desired type of power drive, the same need not be more specifically described.

In my improved construction of pump mechanism per se, i. e. the so-called water end, it will be noted that the same is herein supported on an improved suction member 7, herein performing the dual function of base and suction member and herein having a centrally located inlet or suction 8 (Fig. 5). As shown, this suction inlet is, as preferable, longitudinally disposed and connected at the bottom of the member 7. It also herein has embodied therein large branching suction passages 9 and 10 leading off laterally or transversely in opposite directions from 8 and having large, suitably upwardly curved end passages leading to the suction valves, cylinders, etc., hereinafter described. More particularly, it will be noted that this member 7 has supporting feet 11 on its opposite ends and is provided with suitable flanges 12 and 13 surrounding the upper ends of the passages 9, 10 and connected by suitable bolts to the body of the pump hereinafter described, and that this member 7, which herein forms the suction inlet means, is so disposed relative to the water end that these suction inlet means form the underlying support for the whole of the latter.

Referring more particularly to the structure supported on the suction member 7, it will be noted that this comprises what may be called right and left cylinder sections 15 and 16, each of which is complete in itself and

adapted to cooperate with one of the pump pistons 17, and each of which carries a cylinder 18 and a complete set of suction and discharge valves, hereinafter described. It will also be noted that these parts are so arranged that the passages 9 and 10 lead up at points outside the cylinders 18 (Fig. 5) and are disposed in supporting position beneath oppositely projecting laterally extending 10 passage means forming part of the suction connections leading to the suction valves and located on the outer sides of the sections 15 and 16, while these sections 15 and 16 are herein spaced apart laterally by a central 15 space or aperture between the same. Attention is also directed to the fact that one end of the body or cylinder portion per se of each of the sections 15 and 16 is suitably connected, as by screws, with the adjacent end 20 of the frame 4 of the steam end, which thus serves with the underlying suction means to tie together the two sections 15 and 16, while said underlying suction means supports both the front end of the member 4 and the two 25 sections 15 and 16 and thus combines the functions of a suction supply, a support, and a connecting member. Referring more particularly to the sections 15 and 16, it will also be noted that each carries a pair of suction 30 valves, generally indicated at 19, and a pair of discharge valves, generally indicated at 20, these two sets of valves being disposed at different levels and laterally offset, with the suction valves outside the discharge valves 35 and at a lower level and with a suction valve and a discharge valve at each end of each cylinder, as shown in Fig. 1.

In my improved construction, I have also connected these two sections 15 and 16 by a 40 discharge manifold having transversely disposed branching pipes 21 extending downward and connected to the sections 15, 16 at points between the discharge valves 20 on each of the latter. Thus, it will be observed, 45 not only are the sections 15 and 16 held together by their connection to the underlying suction 7 and to the end of the steam end frame 4, but also by the discharge manifold 21, all in such manner as to produce a very 50 rigid construction. Further, it will be evident that, should it be desired to remove either of the sections 15 and 16 for replacement, as when breakage takes place, either one of these sections may be readily removed as a unit 55 and replaced whenever desired without replacing the other. Here attention is also directed to the fact that the pipes 21 of the discharge lead to a common outlet 22 having therein a usual strainer and communicating 60 with a usual chamber 23.

Referring more particularly to the suction mechanism, it will be noted that the suction passages 9 and 10 in the suction 7 each communicate with a large upper longitudinally 65 extending passage 24 on the outer side of one

of the sections 15, 16. These passages 24 herein branch longitudinally in opposite directions from the upper ends of each of the passages 9 and 10, and herein also are provided at their opposite extremities with suitably curved portions leading to upstanding passage portions 25. At the upper ends of these portions 25 are carried the suction valve mechanisms 19. Herein, it will be noted that these valve mechanisms 19 include a usual cover and spring and a reciprocable ported valve 26, the construction being such that the valve may be removable from the top. It will be understood, however, that any suitable type of valve other than that shown may be used if desired. Moreover, in my present construction the valve 26 of each valve mechanism 19 operates in a suitable annular opening 27 (Fig. 5) in a septum or deck 28 in each of the portions 25 heretofore described, there preferably being one opening 27 in each portion 25 and one valve 26 controlling the same. Also, it will be noted that a relatively large inner passage 29 is provided above each valve opening 27, which extends laterally across and above each cylinder 18, this passage 29 communicating with the adjacent end of its cylinder through an enlarged downward extension 30.

Referring to the cylinders 18 to which the suction is thus delivered, Fig. 4, it should also be noted that a suitable cylinder closure 32 is held in position on the outside end of each cylinder by usual threaded connections 33, one of which herein extends into a stud 34 crossing the chamber 29, and that these members 32 also carry threaded connections 35, functioning to hold the usual liner connections 36 in position. Moreover, the opposite end of each cylinder is provided with a suitably apertured end plate 37, herein formed integrally with the cylinder, having a packing carrying member 38 extending therethrough and permitting the reciprocating piston rod 3 to pass through the packing therein. Each of these members 38 is also seated in a suitable aperture 39 in the end 40 of the frame 4, the latter and the sections 15, 16 being rigidly connected by screw connections 41, which are herein similar to the connections 33, while the member 38 is suitably connected to the end plate 37 by usual removable connections 42 enabling the packing to be renewed as necessary. Also, at each end of the cylinder suitable removable plugs 43 are provided, while each of the members 32 and 40 may also be connected to the cylinder by as many supplemental screws as may be necessary.

The discharge connections to which the discharge is delivered from the cylinders are herein connected directly above the ends of the cylinders 18 and utilize the same passages 30, heretofore described, the discharge valves 44 of the discharge valve mechanisms 20 here-

in being located above the inner end of each passage 29. These valves 44 are herein shown to be similar to the suction valves 26 hereinbefore mentioned, and are adapted to 5 function therewith in the usual manner, the discharge valve shown in Fig. 5, for example, being closed when the suction valve is open. Herein, these discharge valves 44 are also carried in and accessible from the top of 10 standing passage means 45 generally corresponding to the portions 25. Moreover, they also operate generally similarly through a second septum or deck 46 above the level of the suction septum or deck 28, and each functions 15 through a single opening 47. It will also be noted that each of these valves has above the same, in the portion 45, a chamber 48, and that the two longitudinally spaced chambers 48 on each section 15, 16 are connected by a 20 longitudinal chamber 49, herein integral with the sections 15, 16, so that it may receive the discharge from either valve 44; a pipe 21 of the discharge being connected to a suitable opening 50 in the top of each of these chambers 49 so that each discharge valve is thereby, when functioning, directly connected to the discharge.

In the operation of my improved mechanism, it will be evident that as the piston rods 30 of the pump pistons 17 are reciprocated in the usual manner in the cylinders 18, the suction valves 26 and discharge valves 44 also function in the manner usual to double acting duplex pumps. Referring more particularly 35 to the supply connections, it will be observed that the suction 7 will then function through its inlet 8 to receive the fluid to be pumped and supply it laterally and upward through the passages 9 and 10 and into the passages 40 24 and 25. Thus, the liquid is caused to pass not only below the suction valves 26, but directly to them through a minimum of passages and also through passages of such size and length as to minimize the friction and 45 accordingly enable the pump cylinders to fill very completely. More particularly, it will be noted that due to the delivery of the suction through its outlets 9 and 10 at points midway between the ends of the longitudinal 50 supply passages 24, the distance through which the fluid must pass to reach the suction valves 20 is not only shortened, but the passages are made identical for each suction valve. Further, the friction is thus also 55 made the same for the flow of each valve. Attention is also directed to the fact that, due to the large area of the passages 29 between the valves 26 and the cylinders 18, friction here is also minimized, there being no restriction calculated to increase the friction at this point. Thus, a uniform and positive distribution of fluid by the suction valves is insured without eddy currents and with a 60 resultant increased filling of the cylinders and 65 consequent increase in efficiency. Moreover,

the discharge valves are also directly connected to the cylinders by the adjacent or inner ends of these same passages 29 and the passages 30, in such manner as to minimize the necessary passage length between the 70 cylinders and the discharge valves and thereby further reduce the friction. It will also be noted that the discharge valves are so located that the liquid passing through each discharge valve passes directly therefrom 75 into the passageway 49 and therethrough to the discharge 22, the several discharge passages herein also being of equal length for each discharge valve, as in the case of the suction passages. Moreover, it will be noted 80 that the discharge from each discharge valve passes to the discharge without the discharge from one valve in any way interfering or coming near the other discharge valve, thereby further minimizing friction by eliminating any interference of one valve with the action of any of the others.

As a result of my improved construction, it will be observed that it is made possible not only to reduce the friction in both the suction 90 and discharge, but to make uniform the distribution of liquid to each valve in the suction and in the discharge, and consequently increase the cylinder filling function of the suction and the discharge function of the 95 discharge mechanism in such manner as to increase the efficiency of the pump. It will further be noted that while these advantages are obtained, the structure obtained is further improved in such manner as to be exceedingly 100 simple, rugged and inexpensive, involving neither such excessively large and expensive main castings as have heretofore been generally considered necessary in oil field work, nor the necessity for providing supporting 105 means in the form of frames or supports other than provided by the suction inlet means and the steam end supporting means at opposite ends of the structure. Moreover, it is a 110 structure which not only permits of ready access to the parts, but further enables replacements of the same, and even bodily replacements of the cylinder sections, to be readily and inexpensively made. These and 115 other advantages of my improved construction will be clearly apparent to those skilled in the art.

While I have in this application specifically described one embodiment which my invention may assume in practice, it will be 120 understood that the invention is not limited to embodiment in this illustrative form, but may be modified and embodied in various other forms without departing from its spirit or the scope of the appended claims.

What I claim as new and desire to secure by Letters Patent is:—

1. In a pump mechanism including a cylinder and a piston therein, means forming a suction passage extending laterally beneath 130

- and then upwardly at one side of said cylinder, longitudinally thereof, and then upwardly at each end thereof, means constantly forming a lateral chamber above said cylinder at each end thereof adapted to communicate with said suction and communicating with said cylinder, means forming a discharge above each end of said cylinder, and laterally spaced suction and discharge valves at each end of the cylinder controlling the flow through said lateral chamber and disposed in said chamber in vertically spaced decks.
2. In a pump, the combination of a cylinder member having a cylinder therein, suction valves at each end thereof communicating with opposite ends of said cylinder, and means forming a suction for said valves including a suction passage disposed longitudinally of said cylinder and having an inlet midway between its ends and the ends of said cylinder, a suction inlet member connected to said cylinder member midway between the ends of said cylinder and supplying the inlet of said longitudinal passage, and passage means of equal length leading from said longitudinally extending passage to said suction valves.
3. In a pump, the combination of a cylinder member having a cylinder therein, suction valves at each end thereof communicating with said cylinder, and means forming a suction for said valves including a suction passage disposed longitudinally of said cylinder and having an inlet midway between its ends and the ends of said cylinder, passage means of equal length at the ends of said longitudinal passage leading from said longitudinal passage to said suction valves, and a suction member extending transversely of said cylinder member below the latter and connected thereto midway between the ends thereof and of said longitudinal passage and having an outlet opening into the inlet of the latter.
4. In a pump, the combination of a cylinder member having a cylinder therein, upwardly extending passage forming means at each end of the cylinder member communicating with said cylinder at each end of the latter and carrying discharge and suction valves accessible from the top thereof, discharge connections of equal length leading from each discharge valve to a common discharge point including a discharge connection connected to said cylinder member midway between its ends, and suction connections of equal length leading from a common inlet point to each suction valve including a suction connection connected to said cylinder member midway between its ends.
5. In a duplex pump mechanism, means forming a suction having transversely and upwardly extending passages, and longitudinally disposed parallel cylinders disposed above the transverse portions of said passages

and each having on its outer side upwardly leading suction passage means connected to one of the upwardly extending passages of said suction means and to different ends of the cylinder.

6. In a duplex pump mechanism, means forming a suction having a transversely disposed portion provided with upwardly extending passages at its opposite ends, and longitudinally disposed parallel cylinders supported over the transverse portion thereof and between said upwardly extending end passages, each of said cylinders having suction passage means provided with upstanding suction valve passages at opposite ends of the cylinder and connected to an upwardly extending end passage of the suction means.

7. In a duplex pump mechanism, means forming a suction passage having a transversely disposed portion provided with upwardly extending passages at its opposite ends, and longitudinally disposed parallel cylinders supported directly upon and immediately over the transverse portion thereof, each of said cylinders having suction passage means provided with upstanding suction valve passages at opposite ends of the cylinder and connected to an upwardly extending end passage of the suction means.

8. In a duplex pump mechanism, means forming a suction having an elongated transversely disposed portion provided with upwardly extending end passages, and longitudinally disposed laterally spaced cylinders over said transverse portion, each of said cylinders having a longitudinally disposed suction passage disposed on the outer side thereof and connected midway between its ends to an upwardly extending end passage of said suction and at its opposite ends to the opposite ends of said cylinder.

9. In a duplex pump mechanism, means forming a combined suction and cylinder support including passages extending laterally in opposite directions and provided with upwardly delivering passage means at the outer ends thereof, and parallel longitudinally disposed cylinder sections each including cooperating suction passage means on its outer side communicating with the cylinder and with said upwardly delivering passage means and connected to said combined suction and support.

10. In a duplex pump mechanism, means forming a suction having passages extending laterally therefrom in opposite directions and provided with upwardly delivering passage means at their ends, separate longitudinally disposed cylinder sections overhanging said lateral passages, suction and discharge valves located in pairs at each end of each section and connected to the cylinder thereof, cooperating suction passage means on the outer side of each cylinder section and connected to and supported on said upwardly

delivering passage means, cooperating discharge passage means connecting said discharge valves on each section, and a discharge manifold connecting said discharge passage means.

5 11. In a duplex pump mechanism, pump operating mechanism including a longitudinally extending frame having supporting means at one end thereof, laterally spaced longitudinally disposed separate cylinder sections, each connected to the opposite end of said frame, suction means communicating with the cylinder of each of said sections and underlying said sections and connecting the same at the bottom while forming a support therefor and for that end of the longitudinal frame, and a discharge manifold communicating with the cylinder of each of said sections and connecting said sections at the top.

10 12. In a duplex pump mechanism, pump operating mechanism including a longitudinally extending frame having supporting means at one end thereof, laterally spaced longitudinally disposed separate cylinder sections, each connected to the opposite end of said frame, a transverse suction member communicating with the cylinder of each section and underlying said sections and connecting the same at the bottom while forming a support therefor and for that end of the longitudinal frame, and a transverse discharge manifold communicating with the cylinder of each section and connecting said sections at the top, said transverse suction member and transverse manifold each being connected to said cylinder sections at points midway between the ends of the latter.

15 13. In a duplex pump, the combination of a pair of laterally spaced parallel cylinder members, supporting means therefor including a combined suction and foot member underlying both of said members and extending transversely thereof and having an inlet between its ends and upwardly extending outlets at its opposite ends, and connecting means including cooperating suction passage means communicating with said cylinders and said outlets and disposed on the outer side of each of said cylinder members and connecting the same to said combined suction and foot member.

20 14. In a duplex pump, the combination of a pair of laterally spaced parallel cylinder members, a combined suction and foot member underlying both of said members extending transversely thereof at a point midway between the ends of the cylinders, said combined suction and foot member having outlets at its opposite ends, means forming suction passages communicating with said outlets and disposed on the outer sides of said cylinders, each having branching passages leading to the opposite ends of its cylinder, suction valves at each end of each cylinder supplied by said branching passages,

25 discharge valves carried by said cylinders at each end thereof, and a common discharge connected to each cylinder member between the discharge valves on each cylinder member and receiving the discharge therefrom.

30 15. In combination, a plurality of parallel cylinder members having suction and discharge valves accessible from the top thereof and disposed at opposite ends thereof and suction and discharge passages therefor, suction supply means extending transversely beneath each cylinder member midway between the ends of the latter and having passage means of equal length leading from a common inlet and communicating with each suction valve passage, and discharge means midway between the ends of each cylinder member and having passage means of equal length leading to a common outlet and communicating with each discharge valve passage.

35 16. In combination, a plurality of separate cylinder sections spaced laterally from one another and disposed in parallel relation and each comprising a cylinder and suction and discharge valves therefor accessible from the top thereof, suction supply means separate from said cylinder sections and extending transversely beneath both cylinder sections having passage means communicating with each suction valve, discharge means separate from said cylinder sections and extending transversely thereof and the space between the same having passage means communicating with each discharge valve, and means for holding the parts together permitting replacement of a section or sections.

40 17. In combination, a plurality of separate cylinder sections spaced laterally from one another and disposed in parallel relation and each comprising a cylinder and suction and discharge valves therefor accessible from the top thereof, suction supply means separate from said cylinder sections extending transversely beneath each cylinder section and having passage means communicating with each suction valve, means connecting said suction means to each section to hold the parts together releasable to permit replacement of a section or sections, discharge means separate from said cylinder sections and extending transversely thereof and the space between the same having passage means communicating with each discharge valve, and means connecting said discharge means to each section to hold the parts together releasable to permit replacement of a section or sections.

45 18. In a duplex pump, a plurality of parallel horizontal cylinders each having a double acting piston therein and laterally spaced suction and discharge valves at each end of each cylinder accessible from above the cylinders, a common suction inlet midway between the ends of the cylinders and midway between the cylinders laterally, and suction

passages for the valves of different cylinders extending in opposite directions from said common inlet laterally below said cylinders and upward outside the latter to points beneath said suction valves.

19. In a duplex pump, a plurality of parallel horizontal cylinders each having a double acting piston therein and laterally spaced suction and discharge valves at each end of each cylinder accessible from above the cylinders, a common suction inlet midway between the ends of the cylinders and midway between the cylinders laterally, and suction passages for the valves of different cylinders extending in opposite directions from said common inlet laterally below said cylinders and upward outside the latter to beneath said suction valves, the suction passages for the valves on each cylinder having a laterally extending portion in common and branching portions leading to the different suction valves.

20. In a duplex pump, the combination with parallel laterally spaced separate cylinder members having suction inlet means projecting in opposite directions laterally from the outer sides of the bodies thereof, of cooperating transversely extending suction means below said cylinder members and the space between the same and having end passages communicating with said projecting inlet means and underlying and supporting said last mentioned means and with said transverse means forming supporting and connecting means for said cylinder members.

21. In a duplex pump, the combination with parallel laterally spaced separate cylinder members having suction inlet means projecting in opposite directions laterally from the outer sides of the bodies thereof, of cooperating transversely extending suction means below said cylinder members and the space between the same and having end passages communicating with said projecting inlet means and underlying and supporting said last mentioned means, said transverse means also having supporting feet therefor beneath said end passages and inlet means midway between the ends thereof.

22. In a duplex pump, the combination with parallel laterally spaced separate cylinder members having suction inlet means projecting in opposite directions laterally from the outer sides of the bodies thereof and discharge means disposed vertically above the cylinder of each of the same and extending longitudinally thereof, of cooperating transversely extending suction means below said cylinder members and the space between the same and having end passages communicating with said projecting inlet means and underlying and supporting said last mentioned means and with said transverse means forming supporting and connecting means for said cylinder members, and cooperating

transversely extending discharge means connected to said longitudinal means and connecting said cylinder members at the top.

23. In a duplex pump, the combination with duplex pump operating mechanism including a frame having a projecting portion spaced above the bottom thereof, of parallel laterally spaced separate cylinder members having pistons therein operated by said operating mechanism, said cylinder members being disposed beyond one end of said projecting portion and connected to the latter and having suction inlet means projecting in opposite directions laterally from the outer sides of the bodies thereof, and cooperating transversely extending suction means below said cylinder members and the space between the same and having end passages communicating with said projecting inlet means and underlying and supporting said last mentioned means and with said transverse means forming supporting and connecting means for said cylinder members and supporting means for the projecting portion of said frame.

24. In a pump mechanism, the combination with separate cylinder members, of a base on which the cylinder members are separately mounted, said base having a flow passageway communicating with both cylinder members, and having supporting foot portions that extend outwardly and are beneath the outer portions of the respective cylinder members, pistons in the cylinder members, and valves for controlling the flow through the passageway.

25. In a pump mechanism, the combination with separate cylinder members, of a base on which the cylinder members are separately mounted, said base having a flow passageway communicating with both cylinder members and having supporting foot portions that extend outwardly and are beneath the outer portions of the respective cylinder members, said flow passageway having a port opening through the base between said outwardly extending foot portions.

26. In a pump mechanism, the combination with a base and separate cylinder members separately mounted on the base, side by side, each cylinder member comprising a casting having a piston chamber, and a passageway connecting the ends of the piston chamber and having a lateral port opening between its ends, a piston in the piston chamber, valves controlling the flow of fluid between the passageway and the piston chamber on opposite sides of the piston, and a manifold secured to the two cylinder members between their ends and over the lateral ports and constituting a tie between said cylinder members.

27. In a pump mechanism, the combination with a base having end portions and supporting foot portions below said end portions,

said base having a passageway opening through the tops of the end portions, separate cylinder members separately mounted on the end portions of the same and having 5 piston chambers provided with valved communication with the passageway openings therethrough, said cylinder members having other valved passageways in communication with the piston chambers, and a transversely 10 disposed manifold mounted on and connecting the upper portions of the cylinder members and in communication with the last mentioned passageways.

28. In a pump mechanism, the combination 15 with a base having end portions and supporting foot portions below said end portions, said base having a passageway opening between the foot portions and through the tops of the end portions, separate cylinder 20 members separately mounted on the end portions of the base and having piston chambers provided with valved communication with the passageway openings therethrough, said cylinder members having other valved passageways in communication with the piston 25 chambers and having lateral openings between their ends, and a transversely disposed manifold mounted on and connecting the upper portions of the cylinder members and 30 in communication with the lateral ports of the last mentioned passageways.

29. In a pump mechanism, the combination 35 with a base having end portions, foot portions below the end portions and a passageway extending longitudinally through the base and having openings in the tops of the end portions, a pair of cylinder members centrally and individually mounted on the end portions of the base, said cylinder members 40 each having a piston chamber, a longitudinal passageway communicating with the ends of the piston chamber and having its central portion in communication with the passageway opening in the underlying end portion of the base, valves controlling the 45 flow between the passageway and the piston chamber, a piston in each piston chamber, each of said cylinder members having another valve controlled passageway communicating with the ends of the piston chamber 50 and having a central lateral port, and a manifold connecting the tops of the cylinder members and having a passageway in communication with the ports of the last mentioned passageways.

55 In testimony whereof I affix my signature.
JOHN W. GARDNER.
